UNITED STATES PATENT OFFICE.

THEODORE D. PALMER, OF SYRACUSE, NEW YORK, ASSIGNOR TO T. D. PALMER COMPANY, OF SYRACUSE, NEW YORK, A CORPORATION.

COVER FOR PRESSING MEMBERS OF CLOTHES-PRESSING MACHINES.

1,177,572.

Specification of Letters Patent. Patented Mar. 28, 1916.

Application filed July 5, 1913. Serial No. 777,387.

To all whom it may concern:

Be it known that I, THEODORE D. PALMER, a citizen of the United States of America, residing at the city of Syracuse, in the county of Onondaga and State of New York, have invented certain new and useful Improvements in Covers for Pressing Members of Clothes-Pressing Machines, of which the following is a specification.

10 My invention relates to improvements in covers for the pressing members of clothes pressing and like machines.

In certain clothes pressing machines the pressing heads and bucks are provided, for certain classes of work, with a large recess or concave depression, and difficulty has been experienced in making a cover which can be readily applied to and removed from the pressing member or members and at the same time fit or follow the contour of the concave depression mentioned. This difficulty has been overcome by the present invention by which I produce a cover which may be formed of textile material such as 25 canvas or other suitable flexible substance, and may be integral or consist of a number of pieces sewn or otherwise inter-connected and provided around its marginal edge with a cord, string or equivalent, by which the 30 cover may be stretched tightly over the pressing member and secured thereon in a readily detachable manner.

The invention consists therefore in the novel shape, arrangement, and combination 35 of the component members of the cover and the method of tensioning same as herein-after fully described and specifically pointed out in the appended claims, reference being made to the accompanying drawings 40 which show one embodiment of the improved cover and in which—

Figure 1 is a perspective view of a clothes pressing machine provided with my invention. Fig. 2 is a perspective view of the 45 main body of my cover. Fig. 3 is a perspective view of the reverse side of the completed cover. Fig. 4 is a detail of the tie piece. Fig. 5 is a detail of the yoke used to bind the tie piece to the main body of the 50 cover. Fig. 6 is a view showing the parts A, H and J, partially connected together. Fig. 7 is a view of the portions, A, H and J, 55 entirely connected together as they are before folding, for the purpose of forming a channel for the string, P.

Similar letters refer to similar parts throughout the several views.

The main body, A, of the cover is of a size which will cover one of the entire pressing members, B, B, these pressing members 60 being rounded at one end, b, b, and at the other end provided with a concave recess, c, c. To accomplish this, the cover is rounded at one end, d, to fit the rounded end, b, of the pressing member, B, and the other 65 end provided with a concave recess, f, followed at each side by convexly curved edges, g, g, which are continued by concavely curved edges, h, h, to conform to the concave recess, c, and its adjoining parts in the 70 pressing member. To the edge of the recess, f, and edges, g, h, of the main body piece, A, is sewn or otherwise suitably attached one edge of the yoke, H, to the opposite edge of which is attached the tie piece or 75 tensioning member J, which is shaped as shown in Figs. 3 and 4 to correspond to the edges, f, g, h, of the main body piece, A. The yoke, H, is of a width appropriate to the thickness of the pressing member. The edge 80 of the body member, A, is also connected to the tie piece at the points, n, n, shown in Fig. 3. The tie piece also has a curved edge, O. The outer edge, m, of the body member, except where it is connected to the tie piece, J, 85 and yoke, H, is turned over and hemmed or otherwise dealt with to form a channel for the reception of a cord, string, or equivalent, p, and the curved edge, O, of the tie piece, J, is similarly dealt with in continuation of 90 the channel of the body member, as shown in Fig. 3, the cord thus extending around the entire inner circumference with its loose ends at S.

The tie piece may also be provided with 95 apertures, V, V, when required for the passage of bolts or other fastening means, R, by which an additional support sometimes used may be attached to the pressing member.

From the above description, it will be apparent that the cover may be passed over the 100 pressing member with the yoke applied to the recess or concave depression, c, in the end thereof, and that by the described arrangement of the string, tension will be exerted over the whole of the cover to cause 105 same to be closely stretched over said member, the yoke and tie piece which is in a different plane to the main body portion insuring proper fit of the cover at the recessed 110

end of the member due to such tension. When the cover has been sufficiently stretched the ends of the string may be tied to secure the cover in place, and it will also be evident that the removal is equally easy by simply untying the string to release the tension and stripping the cover from the pressing member.

I do not limit myself to the exact shape or arrangement of the parts above described and illustrated in the drawing, since the same might be varied without departing from the spirit of my invention.

What I claim as my invention and desire to secure by Letters Patent is:

1. A cover for the pressing members of clothes pressing and like machines, having a body portion; a tie piece in a different plane to the body portion and a yoke member, the latter connected at opposite edges to the edges of the body portion and tie piece.
2. A cover for the pressing members of clothes pressing and like machines, comprising a body portion; a tie piece; a yoke con-

necting said portions; a tension cord inclosed by the free marginal edge of the tie piece and body portion, whereby tension is exerted to cause the yoke to follow the contour of a concave depression in the pressing member.

3. A cover for the pressing members of clothes pressing and like machines consisting of flexible material shaped at one end to produce a concave depression or recess, having a body portion and tie piece in a different plane to the body portion and a yoke member with a tensioning cord inclosed in the greater part of the marginal edge of the body portion being continued in the free edge of the tie piece, whereby tension is exerted to stretch the cover closely over the whole body of the pressing member.

In testimony whereof I have affixed my signature in presence of two witnesses.

THEODORE D. PALMER.
